LOCATING DEVICE

Lewis F. Weber, New Rochelle, N. Y., assignor to
 United Shoe Machinery Corporation, Paterson, N. J., a corporation of New Jersey

Application October 15, 1935, Serial No. 45,107

5 Claims. (Cl. 33—180)

This invention relates to a device for use in locating two articles in predetermined superposed relation and is herein illustrated as embodied in a device for locating a template on a sole blank preparatory to passing the template and blank through a splitting machine.

In the manufacture of certain kinds of shoes, it is customary to split the sole blank by means of a template and a splitting machine in such manner as to produce an insole having an opening in its forepart and an outsole having in its forepart a corresponding projection. Hitherto, in assembling a template and a sole blank, the operator has depended upon his skill to locate the two articles in proper superposed relation. The object of the present invention is to provide a locating device by the use of which the proper location of two articles, such as a template and a sole blank, with respect to each other may be readily and accurately accomplished.

According to one feature of the present invention, a base plate adapted to receive the superposed articles carries two edge gages located one above the other and adjustable with respect to each other in a path lengthwise of the plate, and two other edge gages located one above the other adjustable with respect to each other in a path crosswise of the plate. In the illustrated device, the two first-named gages have re-entrant work-engaging faces to receive respectively the toe portion of the sole blank and the toe portion of the template; and the two last-named gages have salient work-engaging faces to engage respectively the edge of the shank portion of the sole and the edge of the shank portion of the template.

These and other features of the invention will be described as embodied in an illustrated device and pointed out in the appended claims.

Referring to the accompanying drawings,

Fig. 1 is a longitudinal medial section of a splitting machine specially adapted to have passed through it a superposed blank and template;

Fig. 2 is a perspective of a locating device in which the present invention is embodied, the bracket upon which it is mounted having been omitted;

Fig. 3 is a plan of the device, portions of a sole and a template being shown in place;

Fig. 4 is a section on the line IV—IV of Fig. 3;

Fig. 5 is a section on the line V—V of Fig. 3. The machine of Fig. 1 comprises a stationary knife, an upper vertically adjustable gage roll 11 and a lower yieldingly mounted feed roll 13, both rolls being driven to advance the work to the

knife. In order to hold a superposed template and sole from movement with respect to each other during their passage through the machine, a pair of presser rolls 15, 17 are provided, the shaft of the roll 15 having bearings in a pivoted member 19 which is normally held down in the position shown by a spring 21. After a sole and template have been assembled in proper superposed relation, a treadle is depressed to swing up the presser roll 15 from the other roll 17 so that the sole and template may be thrust between the rolls. The treadle is then released, and the sole and the template are pushed forward until their leading ends are engaged by the rolls 11, 13. The machine thus briefly described above forms the subject-matter of prior application Serial No. 738,325, filed August 3, 1934, in my name.

The device shown in the remaining figures is specially designed for superposing upon a sole blank a template so that, when such blank and template are passed through the splitting machine, the blank is split to produce an insole having an opening in its forepart and an outsole having a corresponding projection. The device comprises a base plate 23 to receive a sole blank 100 and a template 200 in superposed relation. The toe end of the sole blank is engaged by a gage 25 having a re-entrant substantially V-shaped work-engaging face, said gage being slidable lengthwise of the plate on the plate 23 in a guideway formed in the under side of a gage 27 having a re-entrant substantially V-shaped work-engaging face which receives the toe end of the template. Located to engage one edge of the sole blank in the shank portion thereof is a gage 29 having a salient work-engaging face, said gage being slidable on the base plate 23 in a guideway formed on the under side of a similar gage 31 which is fastened to the base plate by screws 33. This last-named gage engages the edge of the template in the shank portion thereof. A short lever 35 pivoted at one end at 37 to the under side of the base plate 23 has at the other end a stud 39 which extends above the upper surface of the base plate a distance slightly less than the thickness of the sole blank. A tension spring 41 attached at one end to a pin 43 driven into the under side of the plate, and at the other end to the head of a screw 44 in the lever, urges the lever to swing clockwise, as viewed in Fig. 3, about its pivot 37. A handle in the form of a pin 45 driven into the lever 35 may be employed to swing the lever in opposition to the force of the spring.

Assuming that the various gages have been adjusted in a manner presently to be described into

the positions shown, the device is operated as follows. The lever 35 is swung out about its pivot 37, a sole blank 100 is placed on the base plate 23 and urged forward until its toe portion engages the gage 25, and the lever 35 is released. Thereupon the spring 41 swings the lever into the position shown in Fig. 3 in which the stud 39 engages one edge of the sole and holds the opposite edge against the shank gage 29. In this way, the sole is located in predetermined position on the base plate. The operator then places the template 200 on the sole with its toe portion against the gage 27 and the edge of its shank portion against the gage 31. After the sole blank 100 and the template have thus been located in the desired superposed relation, they are removed and presented to the splitting machine in the manner which has been described.

The template is commonly slightly larger in outline than the sole blank so as to make sure that the sole blank will be properly supported during the splitting operation. In order to take care of this condition, as well as to accommodate sole blanks and templates of different styles and sizes, provision is made for adjusting the gages. The toe gage 27 for the template 200 is adjustably fastened to the base plate by screws 47 which pass through elongated slots 49 in the gage and are threaded into the plate. The toe gage 25 for the sole blank 100 may be adjusted lengthwise of the plate by turning a small handle 51 having a conical hub 151 which is received in a conical opening in an angular bracket 53 having a downwardly extending arm fastened to the rear edge of the plate 23 by a screw 55. The hub 151 of the handle 51 has a cylindrical socket to receive a short sleeve 56; and a screw bolt 52 having a nut 54 on its lower end, passes through this sleeve, through an elongated opening in the gage 25 and through a bore in the plate 23 to hold the conical hub 151 in the conical opening. It will be noted that there is a recess in the rear portion of the gage 27 into which the horizontal arm of the angular bracket 53 extends. Extending down from the under side of the conical hub 151 is a small pin 57 (Fig. 3) the lower end of which is received in a transverse slot 59 in the gage 25. Consequently, when the handle is turned, the gage is adjusted forward or back. A stop screw 60 having a check nut 62 is threaded through the downturned arm of the bracket 53 and engages the rear edge of the gage 25. The shank gage 29 for the sole is provided with similar adjusting mechanism operated by a handle 61. This handle has a conical hub 161, a screw 67, a sleeve 68 and a nut 65 serving to hold the conical hub in a conical socket formed in the gage 31. The screw passes through an elongated opening in the gage 29 so as to permit adjustment of said gage crosswise of the plate 23. A small pin 670 (Fig. 3) extends down from the bottom of the conical hub 161 into a transverse slot 69 in the gage 29.

The base plate 23 (Fig. 4) has fastened to a downwardly projecting lug on its under side a bracket 71, the shape of bracket being such that when it is bolted to the horizontal top of a bench by a bolt which passes through the hole 73, the base plate 23 will be inclined down from its rear toward its forward end, thereby facilitating the placing of the sole blank upon the plate and the template upon the sole blank in the manner which has been described.

Although the invention has been set forth as embodied in a particular device, it should be

understood that the invention is not limited in the scope of its application to the particular device which has been shown and described.

Having thus described my invention, what I claim as new and desire to secure by Letters Patent of the United States is:

1. A device for locating two sole-shaped articles in predetermined superposed position having, in combination, a plate for supporting the articles in superposed relation, toe gages having re-entrant work-engaging faces adapted to engage the edges of the articles adjacent to their toe ends, said gages being relatively adjustable with respect to each other, shank gages also relatively adjustable with respect to each other and adapted to engage edges of the articles, and means movable independently of the gages for yieldingly holding the lower of the two articles against its shank gage. 10

2. A device for locating two sole-shaped articles in predetermined superposed position having, in combination, a plate for supporting the articles in superposed relation, toe gages having re-entrant work-engaging faces adapted to engage the edges of the articles adjacent to their toe ends, said gages being relatively adjustable with respect to each other, shank gages also relatively adjustable with respect to each other, and adapted to engage edges of the articles, and means extending above the article-supporting surface of the plate a distance less than the thickness of the lowermost article and movable independently of the gages for yieldingly holding the lower of the two articles against its shank gage. 20

3. A device for locating two articles in predetermined superposed position having, in combination, a base plate, a gage adjustably fastened to the base plate, a second gage, and means for adjusting the second gage with respect to the first, said means comprising a handle having a hub rotatable with respect to the base plate and the first gage, and an eccentrically located pin on the hub extending into a slot in the second gage. 40

4. A device for locating two articles in predetermined superposed position having, in combination, a base plate, a gage adjustably fastened to the base plate, a second gage, and means for adjusting the second gage with respect to the first, said means comprising a bracket rigid with the base plate, a handle having a hub rotatable in an opening in the bracket, a bolt passing through the hub, through an elongated opening in the second gage and through a bore in the plate, and a pin located at one side of the bolt, said pin being carried by the hub and projecting into a slot in the second gage. 50

5. A device for locating two sole-shaped articles of sheet material in predetermined superposed relation having, in combination, a stationary base plate, gages carried by the plate, said gages comprising a plurality of toe gages for engaging the edges of articles in the locality of their toe ends, one of said gages being slidably adjustable upon the other longitudinally of the articles, a plurality of shank gages for engaging the edges of the articles in the locality of their shanks, one of said shank gages being slidably adjustable upon the other crosswise of the articles, and means for holding the gages stationary with respect to the base while the sole-shaped articles are being placed in superposed relation upon said base. 60
